UNITED STATES PATENT OFFICE.

HUGH B. HOUSTON, OF PHILADELPHIA, PENNSYLVANIA, ASSIGNOR TO
JAMES E. CALDWELL & CO., OF SAME PLACE.

DESIGN FOR A BREASTPIN.

SPECIFICATION forming part of Design No. 22,258, dated March 7, 1893.

Application filed January 21, 1893. Serial No. 459,254. Term of patent 14 years.

To all whom it may concern:

Be it known that I, HUGH B. HOUSTON, a citizen of the United States, residing at Philadelphia, in the county of Philadelphia and State of Pennsylvania, have invented a certain new and original Design for Breastpins, of which the following is a specification.

My invention has relation to breast-pins, adapted for the use of schools, societies, &c., and consists of the novel, attractive and ornamental design therefor illustrated in the accompanying drawings, wherein

Figure 1 is a front view and Fig. 2 a rear view of the same.

Such design consisting of the representation of a human hand grasping, and supporting at an incline, a baton or staff, the latter, at its lower end, being provided with a spear-head and at its upper end terminating in a ring surmounted by a cinquefoil or five-leaved flower. Secured to the baton or staff, through the medium of a series of hoops which encircle the same, is a flag whose length is considerably less than its width, the greatest extent thereof being in parallel relation with or in the direction of extent of said baton or staff, said flag being looped intermediate the points of its union with the hoops and having its upper, lower and outer edges provided with a straight and narrow border, forming the back or base for a fringe of highly ornamental appearance. Such fringe being composed of a series of heart-shaped figures, in contiguous relation, having their points outermost and their rounded portions adjacent to the border aforesaid, and having interposed between their points similar points or projections. Each of the heart-shaped figures has thereon a pair of small circles, concentric with the curvature of their rounded portions and being each further ornamented by the provision of an approximately diamond-shaped figure, which latter has two of its sides angular and in parallel relation with the edges of the points of the hearts and its other two sides of a curvature corresponding with that of the adjacent circles. While the

intermediate points are also ornamented by the curved lines thereon shown.

The heart at the lower right hand corner of the fringe is provided with an elongated point or extension, having side wings and lined to correspond with the edges of its apex and the point of the heart of which it is an extension. The heart at the upper right hand corner of the fringe being of slightly greater dimensions than the others which compose the fringe.

Passing through the ring at the upper end of the baton or staff is a streamer or ribbon, the shorter end of which extends frontwardly through said ring, curves toward the left, and is notched, as shown, while the longer end or main portion of said streamer floats or curves outwardly, in a like direction, from the rear of the ring and then inwardly to the rear of the flag. Appearing again below the lower edge of the latter, where it assumes a serpentine appearance and has a fold or section thereof curved toward the right, such fold having its end notched, also, and flared.

The hand above mentioned extends laterally from the lower part of the streamer, upon the side opposite to that of the fold.

The main portion or body of the flag is divided, by the diagonal line which extends from the upper left hand to the lower right hand corners thereof, into two triangular spaces or sections which, in practice, are of different colors.

The back of the pin or badge is provided with the usual means whereby the same is secured to the garment of the wearer, as shown clearly in Fig. 2.

What I claim as my invention, and desire to secure by Letters Patent, is—

The design for breast-pins, substantially as herein shown and described.

In testimony whereof I have hereunto set my hand this 12th day of January, A. D. 1893.

HUGH B. HOUSTON.
